UNITED STATES PATENT OFFICE.

JOHN A. HAGERSTROM, OF SCRANTON, PENNSYLVANIA, ASSIGNOR TO VICTOR TYPE-WRITER COMPANY, OF SCRANTON, PENNSYLVANIA, A CORPORATION OF NEW YORK.

RIBBON-REVERSE MECHANISM.

1,362,098.

Specification of Letters Patent. Patented Dec. 14, 1920.

Application filed May 16, 1918. Serial No. 234,923.

To all whom it may concern:

Be it known that I, JOHN A. HAGERSTROM, a citizen of the United States, and resident of Scranton, in the county of Lackawanna and State of Pennsylvania, have invented certain new and useful Improvements in Ribbon-Reverse Mechanism, of which the following is a specification.

This invention relates to typewriting machines and has for its object to provide an improved construction, combination and arrangement of parts in or connected with the ribbon-reversing mechanism. One of the objects of my invention is to provide improved means for automatically varying the printing points on the ribbon corresponding to the successive reversals in direction of the ribbon feed and in this manner prolonging the life and providing for a more efficient utilization of the ribbon. In pursuance of this end, the invention contemplates ribbon-reverse mechanism which after it has been set into operation by the ribbon, will be subjected to an idle period of variable duration before the ribbon-reversing movement is consummated. By this means the last point impinged upon by a type bar in any given run of the ribbon is seldom the same for any other run. Another object of invention is to provide improved means for preventing the simultaneous interlocking of the ribbon driving connections on opposite sides of the machine which often results in locking the main drive shaft and rendering the typewriter inoperative. This sometimes occurs when the beveled driving gears are incorrectly spaced on the drive shaft so that a given endwise displacement of the drive shaft will cause the gears at one side of the machine to come into mesh before the gears on the opposite side have moved out of mesh. Under this condition of things, any subsequent shifting movement of the carriage is quite likely to cause the motor draw band to become displaced. In order to provide suitable and efficient means for overcoming these difficulties, the present invention, according to the embodiment shown on the drawings, contemplates the arrangement of cams on the drive shaft with their webs in close juxtaposition to the bevel gears. These webs are adapted to have running contact with the peripheries of the gears carried by the transmission shaft so that at each end-

wise shift of the main drive shaft, its movement is limited and if the gears thereon have been properly spaced, it is rendered impossible for the bevel gears to be moved beyond their proper intermeshing positions. According to this invention, said cams are each provided with a plurality of cam lobes which project from the webs of said cams parallel to the main drive shaft. These lobes are of sufficient extent and those on one side of the machine are staggered with respect to those on the other side of the machine so that not only is a full endwise movement provided for at each reverse in the ribbon movement, but this arrangement of the cam lobes positively prevents the main drive shaft from being left in a midway position in which it would not be connected up with either transmission shaft.

Other and further objects of invention will appear in the specification and be pointed out in the appended claims, reference being had to the accompanying drawings, in which:

Figure 1 is a general plan view of portions of a typewriting machine constructed in accordance with the principles of this invention, those parts of the machine not directly related to my invention being omitted for the sake of clearness;

Fig. 2 is an end elevation of the same, parts being broken away;

Fig. 3 is a top plan view of the ribbon-winding mechanism, showing contiguous portions of the machine frame and ribbon controlled parts;

Fig. 4 is a similar view with the parts shown in different positions;

Fig. 5 is an elevation taken from above in Fig. 3;

Fig. 6 is a side elevation of the locking rocker;

Fig. 7 is a side elevation from the left side of Fig. 6;

Fig. 8 is a rear elevation of the main drive shaft showing relative positions of parts of the ribbon-reverse mechanism with respect thereto.

Referring to Fig. 1, the drive shaft 1 is journaled in bearings 2, carried by the machine frame. Keyed to the drive shaft 1 are bevel gears 3 and 4, which preferably are in close juxtaposition to the shifting cams 5 and 6, which are provided with lobes 7

and 8, there being in this embodiment of my invention but two cam lobes on each cam, which are arranged diametrically opposite and the lobes of each cam are staggered with respect to the lobes of the other cam. Bevel gears 3 and 4 are adapted to alternately mesh with bevel gears 9 and 10 which are respectively keyed to power transmitting shafts 11 and 12 which, according to Fig. 2, are inclined upwardly and forwardly from the drive shaft 1. The webs of cams 5 and 6 project from the drive shaft 1 to such an extent that when the drive shaft 1 is shifted endwise, one or the other of said webs comes into running contact with that one of the bevel gears 9 or 10 which happens to be brought into mesh at that time. Said cams therefore prevent an overthrow of the drive shaft 1, as pointed out above, and at the same time provide suitable means for locating the bevel gears 3 and 4 on the drive shaft for such artisans as the assemblers and outside repair men. The following description is similar for each end of the machine, but for the sake of convenience will be confined to but one end. Transmission shaft 12 carries at its upper end a bevel gear 13 which meshes with a bevel gear 14 keyed to a spool shaft 15 which is adapted to receive a ribbon spool 16. A ribbon 17 as it is drawn from the spool 16 passes about a fixed axis abutment 18 and between it and a movable abutment 19, which in the present embodiment is constituted by a curved portion of a lever arm 20, which is journaled at 21 in the frame of the machine and rigid with a holding arm or lever 22. The rear extremity of the lever arm 22 normally presses against the upper end of an arm 23 of an interponent lever having a wide U-shaped portion 24 journaled on the transmission shaft 12. At its rear end, the lever 24 is provided with an operating arm 25 which extends inwardly and upwardly to ar- range its rear end over the drive shaft 1. Journaled thereon is a cam roller 26 which is adapted to coöperate with the cam lobes 8 for shifting the drive shaft endwise on its axis. Projecting downwardly from the rear end of the arm 25 is a locating finger 27 which is adapted to bear against the drive shaft 1 in such a manner as to positively locate the cam roller 26 with respect to the edges of the cam lobes 8 by which it is actuated. Referring now to Figs. 3 and 4, a spring 28 has its opposite ends connected to the holding arm 22 and a bracket arm 29 respectively, said spring operating to impart to the holding arm 22 a normal tendency to prevent the interponent lever dropping into operative position. In order to provide the necessary leeway for the ribbon between the fixed and movable abutments 18 and 19, the outer end of the lever arm 20 may be provided with a finger 30 which

may be bent more or less to engage a rigid portion of the frame when the parts are in the desired positions. Keyed to the spool shaft 15 is a star wheel 31, which, as it rotates with the ribbon spindle causes the 70 points or lugs of the star wheel to pass successively over the upper end of a dog 32 which swings about a pivot 33, (see Figs. 6 and 7), carried by a forwardly projecting arm 34 of a rocker or locking member 35. The dog 32 and rocker 35 are preferably made of non-magnetic material such as brass which obviates any troubles which might occur in the presence of large charges of electricity or magnetism. Said rocker is 80 provided with a pair of oppositely disposed pins or trunnions 36 which fit into suitable depressions in the machine frame and serve as a rocking axis for the locking member. From an inspection of Fig. 4 it will be seen 85 that the rocker 35 is relatively heavy in the rear of the pins 36 so that its normal tendency is to raise the arm 34 with the dog 32. Normally, however, this tendency is resisted by the rear end of the holding lever 22 when 90 in the position it occupies in Fig. 3. For this purpose the rocker 35 is provided with a downwardly deflected finger 37 which rests directly upon the holding arm 22. On the forward arm 34 of the rocker 35 is a small, 95 pin or stop 38 which prevents the dog 32 from oscillating in one direction, but permits it to oscillate in the opposite direction, so that when the ribbon spool is rotating in one direction, the lugs or points of the 100 star wheel 31 displace the dog 32 so as to pass readily to permit an easy feed of the machine. Let it be assumed now, that the ribbon 17 has reached a certain point in its travel when a buckle or other rigid body 38, 105 carried thereby, is brought between the fixed abutment 18 and the movable abutment 19 (see Fig. 4). The effect of this condition is to oscillate the holding arm 22 to release the arm 23 of the interponent lever which is 110 therefore permitted to become operative in effecting the shift movement of the drive shaft, in the manner to be presently pointed out. At the same time, the finger 37 being released drops under the unbalanced weight 115 of the rocker, so that the dog 32 is elevated. As soon as the direction of movement of the ribbon has been reversed, the reverse movement of the star wheel 31 is resisted by the dog 32 which is now held against an oscillatory movement on the pin 33 so that one of the points or lugs of the star wheel 31 acts as a cam on the upper end of the dog 32 and thus depresses the arm 34 of the rocker 35 and lifts the locking finger 37 125 which has prevented the rear movement of the holding arm 22. Inasmuch as the moving abutment 19 has now returned to normal position, the spring 28 draws the holding arm 22 into engagement with the lever arm 130

- 23 and thus raises the cam roller 26 out of the way of the cam lobes 8 on the drive shaft. The parts are thus set for another operation. As shown in Fig. 5, the lever 5 arm 20 is disposed within a slot 39 in the curved wall of the spool housing. This wall is provided with a ribbon slot 40 with an opening 41, communicating therewith for the introduction and removal of the ribbon.
- 10 Referring now to Fig. 8, the drive shaft 1 has keyed thereto a collar or spool 42, between the spaced flanges 43 of which projects a pin 44 carried by one arm of an angle lever 45 which is journaled on a stud 46 and provided with a cam segment 47 provided with adjacently disposed notches 48, the inclined walls of which intersect in a point so as to prevent the formation of a neutral point for the yieldably pressed 15 member which co-operates therewith. Said yieldable member is provided in the preferred embodiment of my invention by a lug or projection 49 carried by the lower end of a swinging arm 50 which is pivoted on a 20 stud 51 on the machine frame. A spring 52 is maintained in compression between the frame or bracket and the arm 50 in such a way as to yieldably retain the lug or projection 49 in either of the notches 48. It will 25 be understood from this description that after, according to Fig. 8, the shaft 1 was moved endwise toward the right, the cam segment 47 would be raised until the lug 49 moved over into the lower notch 48 when 30 the pressure of the spring 52 would be utilized in completing the reciprocatory movement of the drive shaft. The operation of the ribbon controlled mechanism has already been described. From an inspection of Fig. 35 it will be evident that whenever the arm 23 is released, the cam roller 26 falls. If it happens that one of the cam lobes 8 is directly beneath said cam roller, its falling movement is interrupted until said cam lobe 40 has moved out from under it, when it immediately drops into position to engage the falling cam lobe which brings about the shifting movement of the shaft. As hereinbefore pointed out, the locating finger 27 45 prevents the roller 26 from dropping too far. It will be understood that in this operation, the lever 19 is actuated at any instant that the buckle 38 comes between it and the fixed abutment 18. This instant 50 occurs independently of the angular disposition of the cam lobes 7 and 8 with respect to one or the other of cam rollers 26. It follows therefore that a roller 26 may fall immediately into the angular notch between the cams 7 or 8 or on to the peripheral 55 surface of one of said cams 7 and 8. In the latter event, said roller 26 is sustained from falling into operative position for a variable period of time depending on the angular position of cam lobe 7 or 8 at the mo-
- ment it comes into engagement therewith. It will be seen therefore that whenever one of the levers 19 is actuated, the ribbon reverse movement may follow immediately or be deferred for a variable period of time depending upon the extent of the peripheral surface of the cam lobe 7 or 8 over which it must be moved before it falls into operative position. The result of this movement is that the ribbon areas which come over the printing point are continuously varied in such a way as to secure maximum efficiency from a given length of ribbon.
- 70 75 80 85 90 95 100 105 110 115 120 125 130
- 1 claim:—
1. In a typewriting machine, ribbon-winding mechanism, and means for reversing the action of said ribbon-winding mechanism, including an element adapted normally to prevent the operation of the ribbon reverse mechanism, and means under the control of 80 said element for locking said element in a position which permits the ribbon reverse mechanism to become operative, said element being operable by the movement of said ribbon to permit said locking means to become operative on said element to lock it in release position.
  2. In a typewriting machine, ribbon-winding mechanism, an interponent lever, a lever normally holding said interponent lever inoperative, said holding lever being adapted to be moved by the typewriter ribbon for releasing said interponent, and means movable into and out of position to lock said holding lever in release position, said holding lever 95 in operative position preventing the operation of said locking means, said locking means being under a normal tendency to move into locking position and provided with means operated by a reverse movement of the 100 ribbon-winding mechanism for moving said locking means to release said holding lever.
  3. In a typewriting machine, ribbon-winding mechanism, an interponent for reversing the direction of winding of said winding 110 mechanism, means normally holding said interponent inoperative, said holding means being movable to release position by said winding mechanism near the end of its movement in one direction, means for locking said holding means in release position, said locking means being operable by said ribbon-winding mechanism to release said holding means.
  4. In a typewriting machine, ribbon-winding mechanism, means for reversing the direction of movement of said ribbon-winding mechanism including an interponent, means for holding said interponent inoperative and movable by said ribbon-winding mechanism 120 into position to release said interponent, and a rocker member provided with a portion movable into and out of position to lock said holding member in release position, and another portion adapted to be engaged by a 130

part of said rocker member for moving said rocker into release position.

5. In a typewriting machine, a main drive shaft reciprocable on its axis, spool shafts spaced therefrom, shafts for transmitting power from said drive shaft to said spool shafts alternately, means for shifting said drive shaft endwise including an interponent lever oscillatable about the axis of each 10 power transmission shaft, a lever for holding said interponent lever in inoperative position, said lever being movable by the ribbon near the end of its movement in one direction, a rocker adjacent each spool shaft, said 15 rocker being provided with an arm adapted to lock said holding lever in release position and another arm by which the rocker may be rocked, means tending to move said rocker into locking position, said holding lever normally preventing such movement, and means 20 carried by the ribbon shaft for operating said rocker.

6. In a typewriting machine, a ribbon winding mechanism comprising in combination 25 a driving shaft, a pair of spool shafts carrying ribbon spools, means for operatively connecting each of said spool shafts with said driving shaft, ribbon-reversing means associated with each spool shaft for 30 operatively connecting up one of said spool shafts and disconnecting the other, fixed and movable abutments adjacent each of said spools, said fixed and movable abutments being adapted to accommodate members carried by a ribbon for displacing the movable 35 abutment, and means controlled by said movable abutment, for operating said ribbon reversing means.

7. In a typewriting machine, ribbon winding mechanism comprising in combination 40 a driving shaft, a pair of spool shafts carrying ribbon spools, gearing for each of said spool shafts for operatively connecting each of said spool shafts with said driving shaft, means associated with each spool shaft for 45 operatively connecting one of said gearings and disconnecting the other, a fixed abutment adjacent each of said ribbon spools, a movable abutment arranged adjacent each 50 of said fixed abutments, said movable abutment being adapted to be displaced by members carried by a ribbon adjacent its ends as said members pass between said abutments, and means controlled by said movable abutment for actuating the connecting and 55 disconnecting means.

8. In a typewriting machine, ribbon winding mechanism comprising in combination 60 a driving shaft, a pair of spool shafts carrying ribbon spools, gearing for each of said spool shafts for operatively connecting each of said spool shafts with said driving shaft, means associated with each spool shaft for 65 operatively connecting one of said gearings and disconnecting the other, an abutment ad-

jacent each of said ribbon spools, a lever having a portion providing an indirect passage for a ribbon around said abutment, said lever being adapted to be moved by an enlargement carried by said ribbon between 70 said abutment and said lever, and means controlled by said lever for actuating the connecting and disconnecting means.

9. In a typewriting machine, a drive shaft, ribbon spool shafts, means for alternately 75 connecting and disconnecting said drive shaft and each of said ribbon spool shafts, ribbon operated means for controlling the operation of said connecting and disconnecting means, said ribbon operated means including a lever arm movable into and out of operative position and provided with a deflected end portion adapted to engage said drive shaft for determining its proper operative position. 80

10. In a typewriting machine, a drive shaft reciprocable longitudinally, power transmitting shafts arranged near opposite ends of said drive shaft, said shafts being provided with gears which are thrown into 90 and out of mesh by the axial reciprocation of said drive shaft, a lever journaled on each transmission shaft, means carried by said drive shaft and levers for alternately reciprocating said drive shaft, said means being movable into and out of engagement by the movements of said levers, and ribbon controlled means for moving said levers. 95

11. In a typewriting machine, a drive shaft reciprocable longitudinally, power 100 transmitting shafts arranged near opposite ends of said drive shaft, said shafts being provided with gears which are thrown into and out of mesh by the axial reciprocation of said drive shaft, a lever journaled on each 105 transmission shaft, means carried by said drive shaft and levers for alternately reciprocating said drive shaft, said means being movable into and out of engagement by the movements of said levers, and ribbon controlled means for moving said levers. 110

12. In a typewriting machine, a drive 115 shaft reciprocable longitudinally of its axis, power transmitting shafts, said shafts being provided with gears by the reciprocation of said drive shaft to connect up one or the other of said transmission shafts with said drive shaft, cams mounted on said drive shaft at different points in its length, levers journaled on said transmission shafts and adapted to move into and out of position to be engaged by said cams for shifting said drive shaft, said cams being provided with axially projecting lobes and said levers being provided with contact bearings to engage the edges of said lobes and with deflected ends adapted to engage the drive 120 125 130

- shaft to locate the bearings with respect to said lobes, and ribbon controlled means for operating said levers.
13. In a typewriting machine, a drive shaft reciprocable longitudinally of its axis, power transmitting shafts, said shafts being provided with gears adapted by the reciprocation of said drive shaft to connect up one or the other of said transmission shafts with said drive shaft, cams mounted on said drive shaft at different points in its length, levers journaled on said transmission shafts and adapted to move into and out of position to be engaged by said cams for shifting said drive shaft, said cams comprising lobes and having the cam lobes at one point of the drive shaft angularly displaced with respect to the cam lobes at another point on the drive shaft.
14. In a typewriting machine, ribbon reversing mechanism, a drive shaft reciprocated by said ribbon-reversing mechanism, and means for holding said drive shaft against endwise movement except when actuated by said ribbon reversing mechanism, said holding means comprising a collar keyed to said drive shaft, a lever pivoted on a fixed axis, said lever having an arm slidably engaging said collar, and notches angularly spaced with respect to said axis, and means yieldably engaging said lever in either of said notches.
15. In a typewriting machine, ribbon reversing mechanism, a drive shaft reciprocated by said ribbon-reversing mechanism, and means for holding said drive shaft against endwise movement except when actuated by said ribbon reversing mechanism, said holding means comprising a collar keyed to said drive shaft, a lever pivoted on a fixed axis, said lever having an arm slidably engaging said collar, and notches angularly spaced with respect to said axis, and means yieldably engaging said lever in either of said notches, said yieldable means comprising a yieldable detent lever pivoted on the frame of the machine and carrying a lug or projection for entering said notches.
16. In a typewriting machine, ribbon reversing mechanism, a drive shaft reciprocated by said ribbon-reversing mechanism, and means for holding said drive shaft against endwise movement except when actuated by said ribbon reversing mechanism, said holding means comprising a collar keyed to said drive shaft, a lever pivoted on a fixed axis, said lever having an arm slidably engaging said collar, and notches angularly spaced with respect to said axis, and means yieldably engaging said lever in either of said notches, said yieldable means comprising a yieldable detent lever pivoted on the frame of the machine and carrying a lug or projection for entering said notches, said notches being provided with inclined sides which intersect without a neutral point between said notches.
17. In a typewriting machine, the combination with a drive shaft, of ribbon-reverse mechanism including a cam arm controlled by the ribbon and a cam mounted on said shaft for engaging said cam arm, said cam having portions which sustain said cam arm out of operating engagement for a variable period of idle movement.
18. In a typewriting machine, ribbon actuated means, a power shaft, and means for operably connecting said ribbon actuated means to said power shaft, said connections including interengageable elements movable respectively by said ribbon actuated means and power shaft, one of said elements after it is moved having an idle period of variable duration.
19. In a typewriting machine, ribbon actuated means, power driven means, a cam arm under the control of said ribbon-actuated means, and a cam driven by said power driven means, said cam being provided with portions which sustain said cam arm in inoperative position during a variable period of idle movement and which subsequently to said idle movements actuate said cam arm for effecting a reverse of the ribbon movement.
20. In a typewriting machine, a main drive shaft, and a power transmitting shaft, one of said shafts having an endwise movement relative to the other, gears on said shaft movable into and out of mesh by said endwise movement, one of said gears being provided with a web or projection extending beyond its periphery and adapted to have running engagement with the periphery of the other gear for limiting the endwise movement of said shaft, and ribbon-reverse means controlling the endwise movement.
21. In a typewriting machine, a main drive shaft, a shaft for transmitting ribbon feed movements from said drive shaft, said shafts being movable into and out of power transmitting relation to each other and having interengageable parts which are moved into and out of engagement by the relative movement of said shafts, a cam provided with a web portion in juxtaposition to one of said interengageable parts which transmit motion between said shafts, and a ribbon controlled arm movable into and out of position to engage said cam for imparting relative movement to said shafts, said web portion of the cam being adapted to engage the other of said interengageable parts to limit the relative movement of said shafts.
22. In a typewriting machine, a main drive shaft, a shaft for transmitting ribbon feed movements from said drive shaft, said shafts being movable into and out of power transmitting relation to each other and having interengageable parts which are moved

- into and out of engagement by the relative movement of said shafts, a cam provided with a web portion in juxtaposition to one of said interengageable parts which transmit motion between said shafts, and a ribbon controlled arm movable into and out of position to engage said cam for imparting relative movement to said shafts, said web portion of the cam being adapted to engage the other of said interengageable parts to limit the relative movement of said shafts, said cam having portions which project laterally from said web portion and sustain said cam arm for an idle period of variable duration.
23. In a typewriting machine, ribbon ac-

tuated mechanism for reversing the direction of movement of the ribbon feed, including cam arms, laterally spaced power transmitting shafts, an endwise movable drive shaft, 20 said power transmitting shafts and main drive shaft being provided with gears for connecting said drive shaft with said transmission shafts in alternation, and cams keyed to said drive shaft adjacent to the gears 25 thereon and constituting guards or stops adapted to engage the gears on said transmission shaft to limit the endwise movements of said drive shaft, said cams and cam arms being adapted to interengage to impart the 30 endwise movements to said drive shaft.

JOHN A. HAGERSTROM.
